UNITED STATES PATENT OFFICE

2,001,103

MEANS FOR ACTUATING FOLDING DOORS

Edmund G. Mathauer, Philadelphia, Pa., assignor to American Car and Foundry Motors Company, New York, N. Y., a corporation of Delaware

Application June 20, 1933, Serial No. 676,648

2 Claims. (Cl. 296—49)

This invention relates to new and useful improvements in means for actuating the folding doors of buses and other vehicles, and comprises doors adapted when in normal closed position 5 to rest in alinement with the side walls of the vehicle, and when in open position, to occupy a position outwardly beyond said normal line and being folded one upon the other.

Another object of the invention is to provide 10 simple, powerful and economical means for actuating the doors to open and closed positions comprising a pneumatically actuated engine positioned preferably under the floor of the vehicle and relatively at one side of the step well 15 leading from the normal floor of the vehicle to the ground.

In the drawings, Figure 1 represents a broken 20 side elevational view of a vehicle, a passenger bus in the present instance, equipped with the invention.

Figure 2 is a horizontal sectional view, the section being taken relatively on the line 2—2 of Figure 1, looking in the direction indicated by the arrow.

Figure 3 is a sectional view, the section being 25 taken on the line 3—3 of Figure 2.

Figure 4 is a sectional view, the section being taken relatively on the line 4—4 of Figure 3.

Figure 5 is a plan view taken on the line 5—5 30 of Figure 3, certain parts being shown in section.

Figure 6 is a fragmentary plan view, partly in section, the section being taken on line 6—6 of Figure 1.

It has been conventional practice in buses of 35 the more modern type to provide a floor of predetermined elevation above the road, upon which floor the passenger seats are secured. If this floor is too high above the road or even the curb line to permit a passenger to step from the 40 normal floor to the street, it is conventional to provide what is commonly called a step well, that is, a depressed floor positioned within the car between the doors and the normal or main floor of the vehicle, thereby providing a more convenient means of ingress and egress for the 45 passengers.

In modern practice the doors are opened and closed usually by pneumatically actuated engines which are connected in some manner with 50 the doors, to open and close the same. These door actuating means comprising the engines referred to, together with certain links and levers, are housed in a convenient receptacle above the normal upper door line.

55 Accidents are sometimes caused by contact

with the housing enclosing such door actuating mechanism and experience has shown that frequent claims for damages have been made because of accidental contact of passengers' headgear or their heads with such housing.

To obviate the disadvantages referred to, this invention provides means including pneumatically actuated engines connected directly with the doors and so positioned as to be entirely out of sight of passengers and in such position that 10 accidental contact therewith is obviated.

To that end the system illustrated in the accompanying drawings is employed, in which A, A¹, B, B¹ indicate compressed air conduits which are connected to opposite ends of the cylinders 15 of pneumatically operated engines 1, which engines are equipped with pistons 2, piston rods 3, relief valves 4, and links or extensions 5, which are pivotally connected at 6, directly to the piston rods 3, said links having extensions 7, which 20 are pivotally connected with the brackets 8, secured directly to the inner faces of those leaves of the folding doors which are nearest in alinement with the engines referred to.

Included in the system is an engine M which 25 may be the one used to propel the vehicle, and may be positioned as shown or elsewhere. Driven by the engine M is an air compressor C connected by conduit 16 to the compressed air cylinder 10, from which leads a conduit 11 to 30 an air control valve 12, which may be a conventional four-way valve of the type illustrated in Patent 999,246 of August 1, 1911, or may be of any suitable construction adapted for the purpose.

As is conventional with this type of valves, an exhaust outlet 13 is provided, and from one side of the valve extends the conduit A which supplies air to the engines of both the front and the rear doors, said conduit comprising the branches A, 40 A, from which lead the branches A¹, A¹, A¹, A¹ directly to the rear or inner ends of the engines 1. The branch conduit B from the valve 12, leads through the branch lines B¹, B¹ to the front or outer ends of said engines so that when 45 the valve 12 is thrown to open communication from the compressed air cylinder 10, air may be sent either to the inner or outer end of each of said engines 1, and if sent to the inner end, the piston 2 will be driven outwardly, that is, in the 50 direction of the doors, thereby, through the piston rod 3, link 5 and extension 7, forcing the doors outwardly to the position shown in dotted lines in Figure 2.

When it is desired to close the doors, the con- 55

trol handle 14 is shifted so as to cut off the air supply from the conduit A, A¹, and direct the compressed air through the conduit B, B¹. To facilitate operation of the engine, relief valves 5 4-4 of conventional design are provided at each end of the engine cylinder so that when compressed air is not being sent from the compressed air valve it may exhaust backwardly through the, connected conduits, the valve 12 and the exhaust 13.

10 The driver's seat 15 is shown in a convenient position to readily enable the driver to control the handle 14 without leaving his seat.

15 For convenience, the engines are housed below the normal or main floor line indicated in dotted lines at 17 in Figure 1 and shown in plan in Figure 2. If desired, the engine may be housed in a sheet metal casing 18, shown in elevation in Figure 3.

20 Preferably the step well opening is made wider for my invention than would be a normal step well so that the engines may occupy the positions shown in Figure 2 without restricting unnecessarily the area of the step wells.

25 Preferably also, the floor 17 is carried across above that portion of the step well in which the engines are positioned, as shown in Figure 3, and over the normal floor is secured an anti-slip tread 9 of conventional design, well known in the art, which anti-slip tread also extends above the engines and their housings in the preferred construction.

30 As will be obvious from the showing in Figure 2, the conduits A, A¹, B, B¹, and 11 and the compressed air cylinder 10 are concealed beneath the floor 17.

35 As the control valve 12 is within the vehicle and about on a level with the steering wheel (not shown), it is obvious that a short length of each conduit 11, A and B from below the floor to the valve 12, is exposed within the vehicle though said conduits are below the floor for the greater part of their length.

40 Figure 6 illustrates certain parts on a larger scale than in Figure 2. For example, the door post E, door D, pneumatic engine 1, link 5, extension 7, and connection 8 with the door.

45 From the disclosure in this figure it will be seen that the brackets 8 are sufficiently removed from the pintle 24 of the door hinge 25 to permit easy 50 operation of the door.

55 Looped about the pintle 24 the hinge straps 25 and 26 are secured, by means not shown, respectively to the door post E and to the next adjacent door section. To position the piston and

piston rod of the engine in alignment with the hinge member 8, the spacing block 26 is provided as shown in Figure 6.

5 Features of merit in the device hereinbefore described when compared with devices for a similar apparatus now on the market, are found to be as follows: (a) Weight—the weight per vehicle of the apparatus described in the present application is about one hundred pounds less than the weight of comparative equipment now on the market where the latter is placed in a cabinet above the doors and applicant's device is placed in the step well. (b) The comparative cost of applicant's device and other devices on the market is as follows: Applicant's device located in 15 step well, less than one-half the cost of competing devices and will produce a saving of nearly three times its cost when compared with similar devices in which a cabinet for the operating mechanism is provided above the doors to be 20 operated including the cost of the cabinet.

The device of applicant is now in service and has demonstrated that it is both efficient and durable as well as economical in production.

25 In accordance with the provisions of the patent statutes, the best embodiment of the invention has been described, but it is to be understood that the drawings are only illustrative and that the invention could be carried out by other means, for example, the arrangement of parts 30 can be modified by placing the engine in a position under the main floor back of the step well, as for example in Figure 2, between the conduits A¹, A¹, as shown at the right hand side of that figure, in which case the conduits A¹ and B could 35 be shortened somewhat, but it would be necessary to lengthen the connection from the piston to the door.

What I claim is:

1. In a vehicle provided with a doorway and a step well, hinged doors normally closing said doorway, a floor for the vehicle, parallel housings at opposite sides of said step well, floor extensions covering said housings, and door operating means enclosed in said housings and being operably connected to the hinged doors at points spaced from the passageway whereby an unobstructed entrance is provided.

2. The substance of claim 1 characterized in that the door operating means is in the form of power motors which have arms extending through the housing and directly connected to the doors at points adjacent their hinges.

EDMUND G. MATHAUER.
